UNITED STATES PATENT OFFICE.

EDWARD B. STEWART, OF ELGIN, ILLINOIS, ASSIGNOR TO WESTERN CASKET HARD-WARE COMPANY, OF ELGIN, ILLINOIS, A CORPORATION OF ILLINOIS.

DESIGN FOR A CASKET-HANDLE.

45,606.

Specification for Design.

Patented Apr. 14, 1914.

Application filed January 20, 1914. Serial No. 813,336. Term of patent 7 years.

To all whom it may concern:

Be it known that I, EDWARD B. STEWART, residing at Elgin, in the county of Kane and State of Illinois, have invented a Design for Casket-Handles, of which the following is a specification, reference being had to the accompanying drawing, forming part thereof.

The drawing exhibits a front view of the casket handle.

I claim:

The ornamental design for a casket handle as shown.

EDWARD B. STEWART.

Witnesses:

GEO. W. GLOS,
F. J. KOSS.
